COTTON PICKER DOFFER

Howard F. Parkerton, South Gate, Calif.

Application April 5, 1951, Serial No. 219,377

3 Claims. (Cl. 56—41)

Generally, this invention relates to mechanical cotton pickers. Particularly, it relates to doffer constructions for the removal of cotton from rotating picking spindles of conventional cotton picking machines.

Conventional cotton pickers include rotating heads each of which is set on a vertical axis and carries a series of radially extending rotating spindles which pass open cotton bolls on cotton plants as the head is rotated and pick the exposed cotton from the bolls by reason of the rotation of the spindles on their own axes and through slight barbing or roughening of the spindle surfaces. As the head rotates, the cotton-bearing spindles in turn pass rotating metallic doffer discs provided with radially extending, vertically projecting rubber pads or fingers which wipe or strip the gathered cotton from the spindles as they pass each other. Heretofore, these rubber fingers have been carried on an annular rubber web clamped to the respective doffer disc by a notched metallic clamping disc as illustrated in the Hagen Patent 2,247,682 of July 1, 1941. These doffer discs possess a number of practical objections including accidental dislodgment of the clamping discs and damage to spindles during operation, replacement costs and also initial costs.

A principal object of the improvements hereof is to provide for low initial cost, to simplify replacements, and to avoid dangers of mechanical injuries to picking spindles and associated parts by displacement or slippage of metal members of the doffer discs while in operation.

Another object is to provide for the industry a metal-free doffer disc.

A further object is to present an integral, all-plastic type of doffer disc, such as an all-rubber disc.

It is a still further object of this invention to reduce replacement costs and also reduce materially the weight of the doffer discs, which, considering the fact that forty such discs are used simultaneously on each cotton-picking machine, is appreciable.

Other objects and the various improvement features of the invention will be apparent to those skilled in the art upon reference to the following specification and the accompanying drawing wherein:

Fig. 1 is an elevational view with parts broken away and shown in section showing a portion of a cotton-picker head with radiating rotatable spindles and two of a vertical series of doffer discs of this invention arranged in operative relation to the picking spindles;

Fig. 2 is a sectional view of one of the doffer discs as taken from the line 2—2 of Fig. 1;

Fig. 3 is a sectional view of the doffer discs taken along line 3—3 of Fig. 1;

Fig. 4 is a fragmentary cross section on an enlarged scale and taken along line 4—4 of Figure 2 illustrating the cohering- or fused-type of integral union between the body of the doffer disc and one of the outstanding fingers or pads thereof, and is representative of a hard rubber disc and a tough, somewhat yieldable rubber doffing finger; and

Fig. 5 is a longitudinal fragmentary section as indicated by the line 5—5 of Figs. 2 and 4.

With reference to Fig. 1, there is illustrated one of a plurality of rotatable heads or supports 10 mounted on a vertical axis on a cotton-picking machine and carrying a plurality of radially projecting picking spindles 12 which are rotated upon their own axes simultaneously with rotation of the head 10 so that the spindles 12 revolve bodily around the axis of the head 10. Spaced somewhat from the head 10 and spindles 12 is a verti-

2

cally disposed rotary shaft 14 carrying thereon a plurality of doffer discs 15 arranged in a vertical series corresponding with the number of picking spindles 12 on the head 10. In practice the uppermost of the doffer discs 15 is held against a shoulder 14a undercut in an upper portion of the shaft 14. As seen in each of Figs. 1, 2, and 3, the doffer discs 15 are provided with hubs 16 having bores to receive the shaft 14 and having keyways to register with corresponding keyways in the shaft 14 for reception of splines 18 by which the doffer discs 15 are driven from the shaft 14.

Each of the doffer discs 15 comprises a disc body 20 which is flat on its reverse or upper side except for a shallow hub portion 21 opposite from the hub 16 on the other side or obverse side. Substantially integrally formed with the disc body 20 on its under or obverse side is a plurality of radially extending, outstanding doffing pads or fingers 22 spaced an appreciable distance from each other. The inner ends of these fingers 22 slope inward to the obverse face of the disc body 20 at an angle of approximately 45°, such sloping being continuous so that the resultant sloping inner ends 23 intersect with said obverse face of the disc body 20. This configuration facilitates stripping of the cotton from the spindles and subsequent release of the cotton so collected. Also, the opposing sides of the various fingers 22 slope to the obverse face of the disc body 20 at a steeper angle than that of the sloping ends 23, thereby yielding opposing sloping sides 24. Between the sloping side walls 24, flat, horizontally disposed tops 25 are provided, these being parallel with the face of the disc body 20. As illustrated, the outer ends of the fingers 22 are in the form of walls 26 which are perpendicular to the disc body 20.

The type of construction represented in Figs. 1 to 5 is such that the disc 20 is formed from thermosetting or thermoplastic material which is relatively hard, although preferably slightly resilient, examples of which are hard rubber compositions, the doffing fingers 22 being produced from somewhat more yieldable material represented by the well known tough tread stock used in the manufacture of automobile tires, the fingers 22 being applied to the disc body 20 in the molding operation and the whole being vulcanized in one operation so that an integral, homogeneous, fused or vulcanized union is produced as indicated at 28 in Figs. 4 and 5. Such a joint is a permanent, tenacious joint which never can be broken in practice apart from the breaking of the hard rubber disc body 20 itself or the rupturing of one of the tough, resilient fingers 22 involved, as is inherent in such a cohesive fused type of union. Such an interlocking or cohesive, fuse-type of union is to be distinguished from an adhesive type of bond existing between totally unlike materials such as those resulting from the vulcanizing or bonding of rubber directly upon metal.

In practice, as above indicated, the plastic materials used have been hard rubber compositions and more yieldable rubber such as tire tread stock which is tough and has long-wearing characteristics. Such rubbers may be either natural or synthetic, as well understood in the art, and the hard rubber may include a considerable proportion of reclaimed rubber or hard rubber dust as also well understood in the art. Hard rubber, for the disc body 20 is valuable, as distinguished from metal, because it is extremely light as compared with suitable metal discs, and also because it offers a certain amount of resilience which resists damage such as is sometimes encountered from foreign materials in the cotton being picked from the bolls. Moreover, hard rubber discs do not result in injury to the picking spindles if they come into contact with each other. Of course, it is important to employ a tough, relatively yielding tread rubber for the fingers 22 because such rubber has long life as compared with hard rubber. While hard rubber fingers 22 could be employed to a limited extent, nevertheless, fingers 22 made of such hard rubber would wear too rapidly from engagement with the spindles, and would not satisfactorily strip off the cotton from the spindles.

While the indicated types of rubber have been found outstanding for practical use, nevertheless it is possible to employ some other types of thermosetting materials,

or thermoplastic materials, where the indicated toughness and pliability are present in the plastic materials used for the fingers 22, and where the disc bodies 20 are produced from plastics having sufficient hardness as well as the indicated resilience, particularly where the indicated types of fused or cohesive joints between the two plastic materials are produced during manufacture. These may include the thermosetting synthetic phenolic types such as phenol-formaldehyde condensation products, and also the thermoplastic synthetic polyvinyl chloride and polystyrene types, as well as rubbers reinforced with resins of the indicated phenolic and styrene types.

In addition to the generally more satisfactory construction of the type of doffing disc of Figs. 1 to 5, which is all of rubber or of other appropriate plastic materials which are thermosetting or thermoplastic, a big factor is its low cost, both from the standpoint of initial cost and from the standpoint of replacement cost, another important factor being a great reduction in weight over the forms heretofore known; for example, reduction from about 2 $\frac{3}{4}$ pounds to about $\frac{3}{4}$ pound per unit. A further important item in favor of this construction is the protection which the hard rubber disc body affords to the picking spindle.

It is intended to protect all variations of the generic invention herein disclosed which fall within the scope of the patent claims.

I claim as my invention:

1. A doffer unit for cotton picking machines including a substantially rigid plastic disc body providing

an axis of rotation; and a plurality of spaced radially directed outstanding fingers mounted adjacent the periphery of said disc body on one face thereof, said fingers being composed of slightly yieldable, tough, plastic material and being permanently secured to said disc body by a homogeneous union providing a substantially integral joint, said plastic material of said disc body being hard rubber and said plastic material of said fingers being tough rubber.

2. A doffer unit as in claim 1 wherein the inner ends of said fingers slope continuously from the tops thereof radially inward to points of intersection with said one face of said disc body.

3. A doffer unit as in claim 1 wherein said homogeneous union is a fusion-type union.
